Primary Examiner — Rhea Shields*(74) Attorney, Agent, or Firm* — Melissa E. Buss(57) **CLAIM**

The ornamental design for a respirator device, as shown and described.

DESCRIPTION

The FIGURE is a perspective view of a nose tab and a chin tab for use with a disposable respirator. In the drawings, the broken lines are for the purpose of illustrating portions of the respirator device that forms no part of the claimed design.

1 Claim, 1 Drawing Sheet(56)
